COMBINED FIREPLACE AND TABLE

William H. Punt, Prescott, Ontario, Canada, assignor to Wallace-Murray Canada Limited

Filed Mar. 27, 1969, Ser. No. 16,476

Claims priority, application Canada Oct. 31, 1968

Term of patent 7 years

Int. Cl. D23—03; D6—01

U.S. Cl. D23—97

F I G. 1

F I G. 2

FIG. 1 is a front perspective view of the combined fireplace and table,

FIG. 2 is a side perspective view of the combined fireplace and table.

The rear of the fireplace is convex and unornamented except for the continuous band of striping and flue pipe.

I claim:

The ornamental design for a combined fireplace and table, as shown and described.
